UNITED STATES PATENT OFFICE

107,414

DESIGN FOR A SHOE OR SIMILAR ARTICLE

Bernard Feldman, Newton Centre, Mass., assignor
to Banner Shoemakers, Inc., West Peabody,
Mass., a corporation of Massachusetts

Application October 9, 1936, Serial No. 65,215

Term of patent 3½ years

To all whom it may concern:

Be it known that I, Bernard Feldman, a citizen of the United States of America, residing at Newton Centre, in the county of Middlesex and Commonwealth of Massachusetts, have invented a new, original, and ornamental Design for a Shoe or Similar Article, of which the following is a specification, reference being had to the accompanying drawing forming a part thereof.

Fig. 1 is a side elevation of a shoe embodying my new design; and

Fig. 2 is a top plan view of the same.

The dominant feature of my design is the arrangement wherein the straps constituting the forepart of the shoe are set off to provide spaced upper and lower groups, the upper group being secured together to form, in effect, a single strap, and the lower group being secured together in pairs, the first and last pair curving in opposite directions, substantially as shown.

I claim:

The ornamental design for a shoe or similar article substantially as shown and described.

BERNARD FELDMAN.
